UNITED STATES PATENT OFFICE.

WILLIAM J. KIRK, OF WELLSBURG, WEST VIRGINIA.

INTERNAL APPLICATOR.

Application filed December 9, 1926. Serial No. 153,558.

My invention relates to the class of internal applicator, more particularly urethral applicators, for the application of medication with accompanying heating, when desired, as hereinafter more fully described.

In the drawings, showing one preferred embodiment of the invention:

Fig. 1 is a view of one form of the device in side elevation;

Fig. 2 is an enlarged longitudinal sectional view through the front end portion of the applicator;

Fig. 3 is a cross section on the line III—III of Fig. 2;

Figs. 4 and 5 show in detail a modified form of cross section and end elevation respectively; and

Figs. 6, 7 and 8 are cross sectional views showing further modified forms of construction.

The applicator as a whole consists of two main members A and B laid side by side, and secured together in any suitable manner to maintain their relationship as a single instrument.

Each is in the form of a tube, made of any suitable material as hard or soft rubber or metal, rounded at the outer closed ends, and of any length and diameter desired. Tube A is the heating tube and tube B is the medication supply tube having near its terminal a plurality of outwardly distributing ports 2. These openings may be of any size, spacing or arrangement, and may extend for a portion or the entire length of tube B as desired.

The inner end portion of tube B is deflected more or less away from tube A, as at 3, for convenience in handling and proper clearance of its terminal connection 4 from the socket 5 of member A.

Terminal connection 4 is socketed for tight insertion thereinto of the delivery end or tip of a standard hypodermic syringe 6, of well known construction. When the syringe is filled to any desired extent and inserted in the terminal 4, its contents will be forced into the tube B, forcing a corresponding amount outwardly through the openings 2 in the form of a spray, jets or streams, along any desired length of the tube. It will be understood that the tube B may be kept filled with the medication, always ready for application and delivery upon the forcing action of the syringe, with accurate regulation of the amount discharged.

Member A is provided with an electrical heater 7, suitably wound for proper resistance through the conductors which extend outwardly through a standard attaching socket 5, for connection with a source of current by terminals 8.

As thus constructed, the applicator is adapted for use and application to any available internal cavity, organ, or tissue.

The particular form of the tubular members A and B is of arbitrary selection, and may be varied as desired. Thus, instead of two cylindrical members, they may be of the form shown in Figs. 4 and 5, with flat confronting faces joined on the line 9, and tapering towards a common blunt point. Otherwise, the double tube construction may be made integral, as in Figs. 6, 7 and 8, with the individual cavities 10, 11, separated by 75 an integral partition 12.

The tips of the members A and B, whether made separate or integral, should be rounded, as shown, to facilitate introduction, and it will be understood, of course, that I do not desire to be limited to either of such alternative forms.

Also, that the applicator may be varied in size or shape to adapt it to various conditions or manner of use, as for instance the accomplishment of dilation in addition to heating and distribution of medication.

The advantages of the invention reside in its simple and economical construction, ease of application and use, and its facility to the objects in view.

What I claim is:

1. An applicator of the class described consisting of a double barrelled elongated multi-tubular body tapered at its outer end providing a common entering terminal and having a middle longitudinal partition forming a closed heater cavity and a perforated medication cavity, a heater in the heater cavity, and a syringe connected with the medication cavity.

2. In an applicator, the combination with a double sided elongated hollow body having a tapered terminal and perforations at one side of the body with a middle longitudinal partition providing a heater cavity at one side and a medication cavity at the other side, of a heater within the heater cavity, and a medication pressure syringe connected with the end portion of the medication cavity.

3. In an applicator, the combination with

a double sided elongated hollow body having a tapered terminal and perforations at one side of the body with a middle longitudinal partition providing a heater cavity at one side and a medication cavity at the other side with a diverging tubular wall forming a rear extension of the medication cavity, of a heater within the heater cavity having a

current supply connection at the rear end of the heater portion of the body, and a medication pressure syringe connected with the rear extension of the medication cavity portion of the body.

In testimony whereof I hereunto affix my signature.

WILLIAM J. KIRK.
